DESIGN FOR A HANDLE FOR EYEGLASSES OR SIMILAR ARTICLES

James L. Donaly, Bloomfield, N. J., assignor to
Frank Kremenz Co., Newark, N. J., a corpo-
ration of New Jersey

Application May 18, 1936, Serial No. 62,700

Term of patent 3½ years

To all whom it may concern:

Be it known that I, James L. Donaly, a citizen
of the United States, residing in the town of
Bloomfield, in the county of Essex and State of
New Jersey, have invented a new, original, and
ornamental Design for a Handle for Eyeglasses or
Similar Articles, of which the following is a
specification; reference being had to the accom-
panying drawing, forming a part thereof.

In the drawing,

Fig. 1 represents a top view of a handle for
eyeglasses or similar articles, embodying my in-
vention,

Fig. 2 represents a front view thereof, and
Fig. 3 represents a rear view thereof.

I claim:

The ornamental design for a handle for eye-
glasses or similar articles, as shown.

JAMES L. DONALY.
